UNITED STATES PATENT OFFICE.

EDWIN A. RUTENBER, OF MILWAUKEE, WISCONSIN, ASSIGNOR TO A. J. LINDEMANN & HOVERSON COMPANY, OF MILWAUKEE, WISCONSIN, A CORPORATION OF WISCONSIN.

ELECTRIC STOVE AND METHOD OF ASSEMBLING THE SAME.

Application filed May 28, 1924. Serial No. 716,334.

The improvements relate to the construction of electrically operated ranges and other heating and cooking apparatus, and their objects are, among others, to provide means for the quick, easy and accurate assemblage of the electrical switches, connections and conductors and their proper arrangement with respect to the range or the like and each other, without necessitating the employment of skilled labor or the making of any measurements or calculations in the assembling operation; to simplify and render more effective the construction of the parts and their manipulation under all normal conditions of use, and generally to improve the construction and operation of said devices and reduce the cost of manufacture.

The improvements are illustrated in the accompanying drawings referred to herein, in which Figure 1 is a side view of the switch and wiring assembly unit of an electric range adapted to the practice of the improvements; Figure 2 is a side view of one of the stove top heating units with prongs for connecting it with the electric conductors; Figure 3 is a plan view of the assembly unit shown in Figure 1, with a heating unit indicated in position thereon; Figure 4 is a side elevation of the heating unit shown in Figure 2 taken at right angles to the point of view of that figure; Figure 5 is an enlarged perspective of one of the connecting blocks for connecting the heating units with the conductors, one of the prongs of the unit being shown in position therein; Figure 6 is a vertical cross section substantially on the line 6-6 of Figure 5 looking in the direction indicated by the arrows in that figure; Figure 7 is a view of one end of the connecting block shown in Figure 5 with a portion of the cover plate removed to expose the interior; Figure 8 is a detail of one of the connecting prongs of a unit in perspective; and Figure 9 is a front view of the switch assembly on a scale reduced from Figures 1 and 3.

In carrying out the invention a frame composed of a trough shaped member 1 and an angular bar 2 extending across it with an overhanging shield 3 is first formed. These members are secured together by suitable bolts or rivets, and form a T-shaped frame.

The trough shaped part is provided with a sliding cover 4 with its inturned edges engaged with the outwardly turned upper edges of the said part 1.

On the outwardly and downwardly turned portion 2a of the bar 2, switch blocks 5 are secured, preferably by means of bolts 7 extending therethrough, and on these switch blocks are mounted switches 6, with conductor wires 8 connected therewith, for closing and breaking the electric circuits. On the frame member 1 connecting blocks 9 are secured, and with these connecting blocks the units 10 are connected, by means of their downwardly depending prongs 11 which engage the jaws 12 of the blocks.

Any desired number of switches may be mounted on the bar 2. For the ordinary range there will be seven or more. Each switch is mounted on a block 5 of insulating material, and the blocks are secured in proper position by their connection with the depending portion of the bar 2 and with an angle bar 13 at their lower ends, the said angle bar being in turn secured to the frame of the stove in any desired manner. Of the seven switches shown (Fig. 7) four—preferably those at the left—control the heating units 10 of the stove top, while the next three in succession control the top oven, bottom oven and broiler (not shown). The particular arrangement however is not important. Ordinary fuse sockets 6a in the switch blocks, connected with their respective switches in any suitable manner provide means for connecting them with service wires, and the connecting wires 8 provide for the closing of the electric circuit through the resistance material of the heating units or other devices so as to give high, low or medium heat, under the control of the switches.

In assembling the parts the T-shaped frame is first placed in position on a temporary frame or "dummy" stove, and the switch blocks bolted thereon. As these blocks and their switches are all alike, and are interchangeable the operator is not required to exercise any selection, but may proceed to secure them in position by working from one end to the other or indiscriminately. After this is done he will—in the

present illustration—secure to the binding posts 14 of the first four switches the shorter wires, the sets of shortest wires for the front top units and the sets of the next longer wires for the rear units. This he will be able to do without any measurement or calculation by observing the lengths of the wires, and securing them to each block in a predetermined order according to their color.

10 The wires are preferably colored, as red, white and green, at their ends, or may be numbered or otherwise marked, and will be secured to the binding posts of the switch blocks and to the connecting binders 15 of the blocks 9 in regular order. Thus the red wire will be connected to the post on the extreme left of the first block, the white wire to the next, and the green wire to the next, and the same system will be followed, beginning with the nearest binder in connecting the opposite ends with the block 9. The wires for the top and bottom oven will then be connected in same manner and run through the trough member 1 and out

15 through the rear thereof, and to the proper binding posts of these devices, the length of the wire in each case indicating the device with which it is to be connected. The cover 4 may then be slid on, and the wiring of the stove is complete. The connecting of the parts other than those connected with the blocks 9, however, is accomplished after the T-shaped frame has been placed in the frame of the range.

20 It will thus be seen that the entire assembling and wiring operation may be performed by unskilled labor, and by one who has no knowledge of the operation of the stove and without any measurements or calculations except such as can be made with the eye. The blocks 9 will be secured to the trough member 1 before the wiring is done, and as these blocks are also interchangeable, the operator requires no knowledge of the

25 operation of the stove.

The construction of the connecting blocks 9 is of importance. Each block consists of a housing of fibre or other insulating material 9^a having a cover 9^b, the cover being secured to the box or housing to the side of the frame member 1 by having a bolt 16 passed through a lug 9^c of the cover and a sleeve 9^d of the box and then through the metal of the part 1, its outer end being secured by a nut 16^a.

The box or hollow block has slots 9^e to receive the prongs 11 of the heating unit, and is divided into a series of compartments by transverse partitions 9^f, each compartment having therein spring contact jaws 12 to receive the connecting prong 11. These jaws are formed of a single piece of spring conductor metal mounted on and secured to an L-shaped conductor arm 17 bolted to the

30 inside of the block by the bolt 18 extending

through the said arm and block wall and having nuts 19 and 19^a on its outer threaded end. These bolts also serve as binding posts to receive the terminals of the wires 8.

The heating unit 10 may be of any desired construction and arrangement suitable for the purpose, and therefore is not described in detail. A manner of arranging the resistance wires therein is indicated at 20, but any other desired form or arrangement may be employed.

It will be seen that the invention herein described not only improves the construction and arrangement of the switches, wiring and connections, but provides means for carrying out a method or process of assembling and wiring which effects a great saving in labor and insures accuracy, without the employment of skilled or highly intelligent labor. Thus it will be seen that a frame for the parts is provided which will receive and hold in proper position the switches, wires and connections and facilitate their proper arrangement and positioning thereon, and that by first cutting the wires in quantities of different lengths, according to their purpose and the position of the parts with which they are to be connected, and marking them to indicate their respective positions and connections, the workmen engaged in assembling the stove are enabled to do the work without any measurement or calculation and by following a few simple instructions, the understanding of which does not involve any knowledge of the nature of the device or its operation. The invention therefore has a two-fold aspect, in that it improves the construction and operation and provides a method of assembling the parts.

What I claim is:

1. An assemblage of switches, wiring and connecting devices for an electric stove or the like comprising a frame having a member provided with means for mounting a series of switches thereon in regular order and a hollow member extending at an angle thereto and connected therewith providing a conduit for wires and also having portions for mounting thereon connections adapted to receive the terminals of heating elements, said parts constituting a unit for the reception and support of the other devices specified herein, switches mounted on the said first member and connecting members mounted on the second member, electric conductors connecting said switches and connecting members and extending through said hollow member, said connecting members having contact devices for receiving the terminals of resistance devices for generating heat, and other wires extending from the said switches through the said conduit to points beyond the frame.

2. A combination of devices such as that specified in claim 1 in which all of the parts,

excepting the heating devices and their terminals, are assembled and secured together to form a single unit.

3. In combination with the parts specified in claim 1, a cover removably connected with the second frame member and covering the conduit and electric conductors therein.

4. The method of assembling the switches, conduits and connections for heating elements of an electric stove which consists in mounting a frame therefor in the frame of the stove, mounting thereon switches and connections to receive terminals of the heating element, cutting a set of attenuated conductors in lengths corresponding with the distances between the terminal connections

and the switches controlling the same, marking the said conductors to indicate the point of attachment of each to its switch and connecting device, then connecting the said conductors with their respective switches and connecting devices according to the indications of their length and marking, by first connecting them to one, then running them through the frame and then connecting them to the other, substantially as herein set forth.

Witness my hand this 13th day of May, 1924, at the city of Milwaukee, in the county of Milwaukee, State of Wisconsin.

EDWIN A. RUTENBER.
